UNITED STATES PATENT OFFICE.

MARTIN HÖLKEN, OF BARMEN-RITTERSHAUSEN, GERMANY, ASSIGNOR, BY MESNE ASSIGNMENTS, TO FÜRST GUIDO VON DONNERSMARCK, OF NEUDECK.

PROCESS FOR IMPROVING PAPER YARN.

No. 805,553.

Specification of Letters Patent.

Patented Nov. 28, 1905.

Application filed April 10, 1905. Serial No. 254,719.

To all whom it may concern:

Be it known that I, MARTIN HÖLKEN, a subject of the King of Prussia, German Emperor, and a resident of Barmen-Rittershausen, in 5 the Province of the Rhine, German Empire, have invented a new and useful Process for Improving Paper Yarn, of which the following is an exact specification.

My invention relates to improvements in a 10 process for improving paper yarn. In the processes hitherto known it was not possible to strengthen the paper yarn and to protect it against moisture in the finishing operation. Many difficulties occur in finishing paper yarn, 15 as it is not admissible to soften the yarn whereby a loosening of the connection would arise, and at the finishing of interwoven yarns a sticking together of the paper threads would easily take place. For these reasons I employ the following process, consisting therein 20 that the paper yarn is only for a short time soaked in the finishing material and is then immediately treated in a brushing-machine, the brushes of which are supplied with paraffin or the like, being either in a liquid or solid state. The yarn in strands or also the single 25 threads may be treated in such a manner. It is of special importance that the yarn immediately after the wetting in the finishing mass 30 is brushed, thereby preventing a loosening of the paper yarn, in which case the yarn would not withstand the tension necessary for the further working. By this immediate brushing it is further obtained that the paper threads, 35 soaked in an adhesive substance, do not stick together.

The process is practiced in the following manner: The paper yarn wound up in hanks is dipped for a short time only into the finishing mass, which may consist of glue, dextrine, 40 potato-starch, or any other adhesive substance, to which oil, fat, or soaps may be added in case a soft yarn is to be obtained. After the wetting the yarn is immediately brought to a brushing-machine and is brushed under tension, 45 while the brushes are supplied with paraffin, wax, fat, or a similar substance. In this manner the superfluous finishing is removed or provided with a cover, whereby the paper threads receive their necessary smooth surface, and at the same time a consistency of 50 the threads is obtained by the brushing of the threads under tension.

Having thus fully described the nature of this invention, what I desire to secure by Letters Patent of the United States is—

The process for improving paper yarn, consisting therein, that the yarn is for a short time dipped into a finishing material and is immediately thereafter treated under tension 60 in a brushing-machine, the brushes of which are supplied with paraffin, wax, fat or the like, substantially as described and for the purpose set forth.

In witness whereof I have hereunto set my 65 hand in the presence of two witnesses.

MARTIN HÖLKEN.

Witnesses:

HENRY HASPER,
WOLDEMAR HAUPT.
